UNITED STATES PATENT OFFICE

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA

EXHAUST-BOX-FLOOR CONSTRUCTION

Application filed May 16, 1928. Serial No. 278,091.

My invention relates to exhaust boxes used in the canning art, and, although not limited thereto, is particularly adapted for the well known disk type of box.

5 The principal object of the invention is to provide an improved floor or bottom for exhaust boxes, which is inexpensive and simple to construct, easy to keep clean, and light in weight yet of sufficient strength and rigidity 10 to support the interior mechanism of the box. My invention eliminates all interior frame work in the box, the entire mechanism being supported directly upon the floor or bottom.

15 The above and other objects and advantages of the invention will be fully described in the following specification, which should be read with the understanding that the form, construction, and arrangement of the several 20 parts may be varied, within the limits of the claims hereto appended, without departing from the spirit of the invention as set forth in said claims.

Reference should be had to the accompanying drawing, wherein Fig. 1 is a plan view, 25 with the cover removed, of a portion of a disk type exhaust box embodying a preferred form of my invention.

Fig. 2 is a section on the line 2—2 of Fig. 1. 30 Fig. 3 is a sectional detail on the line 3—3 of Fig. 2.

In the drawings, the reference numerals 1 35 designate suitable vertical supports, or legs, to which are secured the sides 2 of the box. 3 are the disks which form the can conveyer in the usual manner, and 4 are guides for establishing the tortuous can path. The disks 3 are suitably inter-connected for rotation in the proper direction, preferably by 40 having intermeshing teeth formed in their edges, as shown at 5 in Fig. 2. This construction being well known in the art, and forming no part of the present invention, said intermeshing teeth have been omitted from 45 Fig. 1 for the sake of clearness. Suitable means for driving the disks 3 is indicated in Fig. 2 by a shaft 6, a pinion 7, and a gear 8 meshing with said pinion and secured to one of the disks 3.

50 The bottom or floor of the box, which is an

essential feature of the present invention, comprises a series of raised deck portions 9 separated by troughs 10. I prefer to make the troughs parallel and extending lengthwise of the box, although this is immaterial. 55 For ease of manufacture, I prefer to make said troughs rectangular, as shown, although they may be of other shapes, and I prefer to make the floor in sections, welded or otherwise joined together as shown at 11, and 60 welded or otherwise joined to the sides 2. Using this construction, the floor can be made of comparatively light sheet metal, and the bends can be made quickly in a simple press. It is entirely possible, of course, to make the 65 floor in one piece by using a more elaborate press, but on account of the size, running six feet in width and from 10 to 25 feet in length, I find it more economical to use the sectional construction as shown. 70

The disks 3 are mounted directly upon the raised decks 9, by any suitable means, as for example flanged bosses 13 in which are fixed spindles 14, the disks rotating upon said spindles and their upper ends carrying the 75 guides 4 by means of brackets 15. I prefer to mount two rows of disks upon each raised deck, as shown, although any other convenient arrangement may be adopted. The troughs 10 so stiffen the entire floor that ample strength and rigidity are obtained even from comparatively light sheet metal. If desired, a flat plate 16 may be placed beneath the floor for additional stiffness, and secured to the bottoms of the troughs by any suitable 85 means, although the use of such additional plate is optional.

At one position in the length of the box, a transverse drain pipe 17 is secured, by any means, not shown, to the bottom of the floor. 90 The upper half of said pipe is cut away where it intersects the troughs 10, as shown in Fig. 3, and the bottoms of said troughs are similarly cut away where they are intersected by the pipe. There is thus a free opening into 95 the pipe from each trough, as shown at 17' in Fig. 1, and any liquid which collects in said troughs runs into said pipe and is carried away. More than one pipe may be used if desired, and it is preferable to make the 100

troughs, or the entire floor, with a slight slope downward toward the pipe or pipes to facilitate draining.

Openings are preferably provided in the 5 sides of the box, one such opening being shown at 18 in Fig. 2, covered by a suitable removable plate or door 19. By directing a stream of water from a hose through said openings, the raised deck portions 9 and the 10 disks 3 can be washed off, the water flowing into the troughs 10 and out through the drain pipe 17. There being no interior frame work necessary to support the disks, the entire box 15 can be cleaned easily and quickly by flushing with water as described.

I claim:—

1. In an exhaust box, a floor comprising a sheet of metal bent to form a raised deck and an adjacent depressed trough, and can conveying means mounted upon said deck.
2. In an exhaust box, a floor comprising a plurality of sheets of metal having their edge portions bent and joined together to form raised decks separated by a depressed trough, 25 and can conveying means mounted upon said decks.
3. In an exhaust box, a floor comprising a raised deck and an adjacent depressed trough, a drain intersecting said trough, and can conveying means carried by said deck.
4. In an exhaust box, a floor comprising a sheet of metal bent to form a plurality of raised decks and adjacent depressed troughs, a drain conduit extending across and intersecting said troughs below the level thereof, 35 and can conveying means mounted on said decks.
5. In an exhaust box, a floor comprising a raised deck and an adjacent depressed trough, 40 and a drain pipe extending across below said trough, the top of said pipe and bottom of said trough being cut away to form a communicating aperture.
6. In an exhaust box, a floor comprising a plurality of raised decks and intervening depressed troughs, and can conveying means mounted upon said decks.

In testimony whereof I have signed my name to this specification.

50 ALBERT R. THOMPSON.
